UNITED STATES PATENT OFFICE.

WILLIAM H. CAMP, OF WOODVILLE, CONNECTICUT.

DOOR AND WINDOW SCREEN.

1,182,749.

Specification of Letters Patent.

Patented May 9, 1916.

Application filed June 12, 1914. Serial No. 844,769.

To all whom it may concern:

Be it known that I, WILLIAM H. CAMP, a citizen of the United States, residing at Woodville, in the county of Litchfield and 5 State of Connecticut, have invented certain new and useful Improvements in Door and Window Screens, of which the following is a specification.

This invention relates to window and door 10 screens, especially aiming the eliminate trapping of flies on the interior of a building, and it is the principal object of this invention to construct the door and window screens in a novel manner permitting the 15 escape of the flies or similar animate beings which find their way into a building, permitting them to escape and precluding their entrance, at least to a considerable extent.

Another object of the invention resides in 20 the utilization of a reinforcing strip for the margin of the screen, adjacent the escape opening; the strip operating in a dual capacity, since in conjunction with reinforcing the marginal edge of the screen above referred to, it likewise provides an abutment 25 on the interior of the screen, reducing the possibility of the entrance of flies to a minimum.

A further object is to provide extensible 30 window screens having suitable means in engagement therewith for retaining the sections in a predetermined position.

Other objects as well as the nature, characteristic features and scope of my invention will be more readily understood from 35 the following description taken in connection with the accompanying drawings and pointed out in the claims forming a part of this specification.

40 Referring to the drawings: Figure 1 is a front elevational view of a screen constructed in accordance with my invention, Fig. 2 is a transverse sectional view taken on the line 2-2 of Fig. 1, Fig. 3 is a detailed enlarged fragmentary sectional view taken on 45 the line 3-3 of Fig. 1, showing the manner in which the screens are held in a predetermined adjusted position, Fig. 4 is a modified form of window screen, illustrating 50 its application, Fig. 5 is a front elevation of a screen door embodying my invention, Fig. 6 is a longitudinal sectional view of the same, and Fig. 7 is a detailed enlarged 55 sectional view of the upper end of the door and window, showing the manner in which

the reinforcing strip is detachably secured thereto.

In the drawings wherein is illustrated the preferred embodiment of this invention, screen-sections 5 and 6 are provided which 60 are slidably engaged in guides 7, the latter being made of metal and having the marginal edges 8 thereof turned at right angles to the body to provide a channel for preventing displacement of the screen-sections, 65 the section 5 being detachably secured thereto by screws 9.

Each of the sections 5 and 6 has a wire screening 10 mounted therein, one end of each of the screenings being engaged with 70 one of the sections, while the opposite end thereof is engaged with a bar 11, in order to insure the rigidity of the screen. A marginal edge of the screening in each of the sections 5 and 6 is remote from its frame so 75 as to provide an opening 12 therebetween and the frame which forms the exit for the flies. Each of said remote marginal edges of the screening 10 is engaged by a reinforcing strip 13, the latter in the present 80 instance comprising a sheet-metal plate which has the opposite edges thereof turned into parallelism with each other and engaged with the screening, as shown to advantage in Fig. 2, said reinforcing strip lying at right angles to the screening 10, so as to provide abutments for precluding, as 85 much as possible, the entrance of the flies, since it is seen that flies crawling on the screening will be retarded in their course, so as to reduce the possibility of their entrance 90 to a minimum. The lower portion of the reinforcing strips 13 is spaced from the vertical screening, thus forming a cavity into 95 which the fly enters in its movement up the screening and from which it is necessary to fly, as the edge of the strip forms an adequate barrier to his journey along the horizontal section of the screening. The reinforcing strips 13 are detachably engaged 100 with the respective sides of the frames 5 and 6, by screws 14, spacing sleeves 15 being mounted on the shanks of the screws, so as to limit the movement of the strips 13, in order that a predetermined space will be 105 provided between the strips and the sides of the sections with which the screws 14 are engaged.

As is obvious, the screen-sections 5 and 6 may be adjusted to fit windows of various 110

sizes, suitable means generally designated 16, coöperating with the sections to hold the latter in predetermined adjusted positions, said means in the present instance comprising a rack-bar 17, which is carried by the screen-sections 5, while a spring-locking element 18 is mounted on a plate 19 on the section 6, for engagement with the rack-bar 17, the locking element 18 providing a beveled side and an abrupt side, conforming to the contour of the rack-bar, so as to permit sliding of the sections in one direction, but preventing their operation in the opposite direction, unless it is disengaged from the rack-bar. The provision of the means 16 further prevents sliding of the sections 5 and 6 from the exterior, since the sections will be in their extendedmost positions for engagement with the window 29 casing thereby preventing their movement in that direction, while relative movement will be prevented toward each other in view of the abrupt side of the locking-member 18 which engages with the complemental abrupt portion of the rack-bar 17.

My improved fly escape has been shown as associated with a door, the door-frame in the present instance being indicated at 19 and being of the usual or any desired configuration, having a screening mounted therein which is secured to the frame through the medium of the usual reinforcing strips 21. The upper marginal edges of the screening 20 is remote from the upper end of the frame 19 and is engaged with a reinforcing strip 22, the latter in the present instance being similar to the reinforcing strip 13 of the window sections 5 and 6, the strip 22 being likewise formed from a metal sheet and folded upon the remote margin of the screening 20, said strip lying at right angles to the screening to provide an abutment, the opposite ends 23 of said strip extending into engagement with the opposite sides of the door-frame 19. A reinforcing strip 22 is detachably engaged with the upper end of the door-frame 19 by screws 24, the screws having engaged on the shanks thereof spacing sleeves 25, in order to retain the reinforcing strip 22 in spaced relation to the inner marginal edge of the upper end of the door-frame. Similar to the strip 13, the lower portion of the strip 22 is spaced from the screen forming a pocket between the strip and screen from which the fly has to fly to leave because of the abutment formed by the edge of this portion of the strip.

In Fig. 7 the specific manner in which the reinforcing strip is engaged with the screening 10 or 20, and the manner in which the reinforcing strip is secured to either of the window sections or the door, is shown. However, it is immaterial to which it is secured and the formation is identical in

either instance, hence an object indicated 26 is indicated in Fig. 7 which may be either the door or window as desired.

The construction shown in Fig. 4, discloses the usual wire screening 27 which has the upper marginal edge thereof in engagement with a bar 28, the latter being made of wood, metal or any other suitable material and extending outwardly from the window casing so as to provide an abutment, and being secured to the window casing in any suitable manner, said bar being adapted for engagement with the window 29 which is mounted thereabove in the window casing, it being seen that a space 30 is provided between the bar 28 and the lower marginal edge of the window 29 through which the exit of the flies is permitted, but will preclude their entrance in view of the abutment provided by extending the bar 28 outwardly from the window frame. The view shown in Fig. 4 is one taken from the interior of the window casing with which the screen is associated, since the manner of connection to the window frame, etc., is immaterial.

In operation of the device when used as a window screen, it is seen that the sections 5 and 6 are adjusted to conform to the size of the window frame in which the screen is mounted and it is seen that the sections will be held in a locked position when adjusted in the window casing in view of the coacting locking means 16, this likewise preventing actuation of the sections 5 and 6 from the exterior of the window in which they are mounted, permitting of their expeditious relative movement from the interior of the casing by merely disengaging the locking member 18 from the rack-bar 17.

It will be understood that the above description and accompanying drawings comprehend only the general and preferred embodiment of my invention and that various minor changes in details of construction, proportion and arrangement of parts may be made within the scope of the appended claims and without sacrificing any of the advantages of my invention.

Having thus fully described my invention, what I claim as new and desire to secure by Letters Patent is:

1. A device of the character described including a frame, screening mounted in the frame, one of the marginal edges being remote therefrom, and a reinforcing strip carried by said remote margin, the margin being at right angles to the screen for preventing the entrance of flies.

2. A device as specified including a frame, screening mounted in the frame, one of its margins being remote therefrom, a metallic strip folded upon the remote margin of the screening to reinforce the latter and the strip engaged margin being bent at right angles.

angles to provide an abutment for precluding the entrance of flies.

3. A device as specified including a frame, a wire screening mounted in the frame, one of its margins being remote therefrom, a reinforcing strip carried by said remote margin, the margin being at right angles to the screening to provide an abutment for precluding the entrance of flies, and means 15 passing through said reinforcing strip to secure the screening thereto and for detachably engaging the abutment with the frame.

4. A device as specified including a frame, wire screening mounted in the frame, one of its margins being remote therefrom, a reinforcing strip carried by said remote margin, the margin being at right angles to the screening to provide an abutment, said strip comprising a sheet-metal plate, the longitudinal edges of which are bent into engagement with said remote margin, screws extending through said reinforcing strip and being engaged with said frame for detach- 20

ably engaging said reinforcing strip therewith, and a sleeve mounted on each of said screws for holding the reinforcing strip in spaced relation to the frame. 25

5. A device as specified including a frame, screening mounted in the frame, one of its margins being remote therefrom, a reinforcing strip carried by said remote margin, the margin being at right angles to the screening to provide an abutment, said strip comprising a sheet metal plate, the longitudinal 30 edges of which are bent into engagement with said remote margin, the lower portion of said strip spaced from the screening, and means for securing the abutment to the frame. 35

In testimony whereof I affix my signature 40 in presence of two witnesses.

WILLIAM H. CAMP.
